US00D765120S

(12) United States Design Patent
Kim et al.

(10) Patent No.: US D765,120 S
(45) Date of Patent: * Aug. 30, 2016

(54) DISPLAY SCREEN OR PORTION THEREOF
WITH GRAPHICAL USER INTERFACE

(71) Applicant: Samsung Electronics Co., Ltd.,
Suwon-si (KR)

(72) Inventors: Bowon Kim, Busan (KR); Jeewon Lee,
Seoul (KR)

(73) Assignee: SAMSUNG ELECTRONICS CO.,
LTD., Suwon-Si (KR)

() Term: 15 Years

(21) Appl. No.: 29/529,135

(22) Filed: Jun. 4, 2015

(30) Foreign Application Priority Data

Feb. 27, 2015 (KR) 30-2015-0010386

(57) CLAIM

The ornamental design for a display screen or portion thereof with graphical user interface, as shown and described.

DESCRIPTION

The FIGURE is a front view of a display screen or portion thereof with graphical user interface showing our new design. The outermost broken lines show a display screen or portion thereof and form no part of the claimed design. The broken lines showing portions of the graphical user interface form no part of the claimed design.
